UNITED STATES PATENT OFFICE.

HARRY C. ROBINSON, OF MUNCY, PENNSYLVANIA.

GRINDING-MILL.

No. 823,365.

Specification of Letters Patent.

Patented June 12, 1906.

Application filed March 17, 1903. Serial No. 148,215.

To all whom it may concern:

Be it known that I, HARRY C. ROBINSON, a citizen of the United States, residing at Munsey, in the county of Lycoming and State of Pennsylvania, have invented new and useful Improvements in Grinding-Mills, of which the following is a specification.

This invention relates to grinding-mills, and it is of particular adaptation to that class of mills having one or more pairs of horizontally-disposed grinding-rolls the peripheries of which are adapted to travel approximately in contact, although, of course, I do not intend to limit myself in this respect, for some of the features of the invention may be employed with equal facility in mills of other kinds.

The objects and advantages of the invention will be set forth at length in the following description, while the novelty thereof will be covered in the claims succeeding such description.

Said invention is shown in one simple and convenient embodiment thereof in the drawings accompanying and forming a part of this specification, and in which—

Figure 1 is an elevation as seen from one side of the machine. Fig. 2 is a similar view as seen from the opposite side thereof. Fig. 3 is a sectional elevation of the same viewed from the same side thereof as that illustrated in Fig. 1. Fig. 4 is a detail view in sectional elevation of part of the means for shifting the movable bearings of one of the grinding-rolls. Fig. 5 is a like view of an adjustable or movable bearing. Fig. 6 is a diagrammatic elevation showing the pulleys and belting employed for driving the grinding-rolls, the machine and certain other parts being shown by dotted lines.

Like characters refer to like parts throughout the several figures.

The framework for carrying the different parts of the machine may be of any suitable character. That represented is denoted in a general way by 2 and is provided upon its top with bearings, hereinafter more particularly described, for the grinding-rolls, there being in the present case two pairs of these rolls which, as is customary in this type of mill, are operated at differential speeds.

The said two pairs of rolls are housed in the casing 3, which rests upon the framework. Both the framework and the casing 3, mounted thereon, are all of a construction familiar in this art, and for this reason it is unnece-

sary to describe the same in detail. The casing is provided with the usual feed-controlling devices.

As previously indicated, the machine in the present instance involves two pairs of grinding-rolls. Each pair involves a high speed and a low speed roll, and the ratios of velocity between the same may be that ordinarily employed in this art. The fast-speed roll is generally driven at six hundred revolutions to the minute, or in this neighborhood, while the low-speed roll is driven at from one hundred and fifty to two hundred revolutions to the minute. The high-speed rolls are denoted by 4 in each case, the low-speed rolls being designated by 5, and their peripheries or working surfaces run practically in contact, said low-speed rolls, as will hereinafter appear, being adjustable toward and from the companion or high-speed rolls in order to regulate the character of the product of the machine. The bearings for the shafts of the high-speed rolls are denoted by 6 and are stationary and located at opposite sides of the framework 2. The bearings 6 are generally made integral with the framework.

The bearings for the shafts of the low-speed rolls are shown at 7 and are movable toward and from the respective stationary bearings in order to provide either for the adjustment of the rolls or for throwing them out of action when the machine is not grinding or for other purposes.

The bearings 7, which, as is understood, are bodily shiftable relative to the stationary bearings, consist, preferably, of slides mounted in some suitable manner upon the framework. They may be mounted as indicated clearly in Fig. 5.

As it is necessary in mills involving two grinding-rolls traveling approximately in contact to drive one of said rolls at a higher speed than the other, it is my intention to drive the rolls supported by the stationary bearings at a higher speed than the other rolls. An advantage follows this. When the adjustably-mounted rolls are driven at a high speed, there is a decided tendency when the rolls are in operation, due to their high velocity, to loosen the adjusting means, so that accuracy in the grade of the product is not assured. To overcome such derangement of the adjusting means, I drive the adjustable rolls at a low speed, the high-speed rolls being supported by fixed bearings. It

will be seen that the movable bearings 7 are both on the same side of the coöperating fixed bearings, by virtue of which the belting which is employed to operate the rolls can be arranged in a very compact manner, thereby saving considerable space, which is an important factor.

In Fig. 6 I have illustrated diagrammatically the driving mechanism for operating the coöperating rolls.

Upon one end of each of the shafts of the high-speed rolls is fastened a pulley 8, the shafts of the low-speed rolls carrying like pulleys 9 at the opposite side of the machine. The driver for the highest-speed rolls is denoted by 10 and is supported upon a line-shaft 11, mounted upon the hanger 12, fastened to the under side of the floor upon which the mill is mounted, said floor having, of course, openings for the passage of the driving-belts. The belt for transferring motion from the driving-pulley 10 to the pulleys 8 is denoted by 13 and is passed under the lower half of the driving-pulley and over the upper halves of the horizontally-aligned driven pulleys, it having a depending bight between the outside runs thereof, passing around the under portion of the idler-pulley 14, mounted on the framework 2 just below the two driven pulleys 8. The driver for the low-speed rolls 5 is designated by 15, and it is fixed to the same line-shaft 11 to which the high-speed driver 10 is secured. Said shaft 11 may be operated in any suitable manner. The driving-belt for transferring the motion from the pulley 15 is shown at 16, it passing around the under side of said driver or pulley 15 and around the upper sides of the pulleys 9, the outer branches of the band extending downward and around the idler or guide pulley 17, supported suitably by the hanger 12' below the line-shaft 11. The two drivers 10 and 15 are operated in unison from the same shaft, and as they are of different diameters, as illustrated, they serve to transmit, through the intermediate belting and other parts, proper relative speeds to the grinding-rolls of the respective pairs. In the diagrammatic figure numbered 6 I have illustrated by arrows the direction of movement of the belts, pulleys, &c., which figure shows the compact arrangement of the several parts.

It will be understood that the movable bearings 7 for the low-speed rolls 5 have been set forth as consisting of horizontally-movable slides, by virtue of which the slides can be manipulated to adjust the low-speed rolls relatively to the companion high-speed rolls or to move said rolls entirely away from the companion rolls in case it is desired to stop the grinding or in case any unusual obstruction should be caught between such rolls. I provide means for shifting simultaneously or individually the bearings for the low-speed rolls. The means for bodily shifting the

movable bearings either simultaneously or separately will be hereinafter described.

In connection with the low-speed rolls I provide means for trammimg the same, whereby the surfaces of the respective rolls can be brought into absolutely correct grinding relation, and the trammimg means, as will hereinafter appear, operate entirely independently of the adjusting and shifting mechanism for said low-speed rolls, whereby the latter can be bodily shifted without affecting their set after they have been trammed.

Each movable bearing 7 includes in its make-up a pivoted block 20, which directly sustains the journals of a low-speed roll and which is mounted upon the body of the bearings. Referring to Fig. 3, it will be seen that both pivoted blocks are mounted upon what is represented as being the left side of the respective bodies of the movable bearings 7. Each pivoted block is provided at the side thereof farthest from the pivot with a projecting flange or toe, through the outermost side of which is tapped a screw 22, the lower end of which is adapted to bear against the upper horizontal face of the body of the bearing or slide 7, which body is fixed relatively to the pivoted block. The toes or flanges 21 between the vertically-disposed screws 22 and the pivots thereof are perforated to receive the vertically-disposed screws 23, the heads of which are adapted to fit against the upper sides of said flanges and the lower ends of which are tapped into the bodies of the movable bearings or slides 7. There are two of these screws 23 in each case, as clearly shown in Fig. 5.

It will be assumed that it is desired to lower the end of the roll 5 on the left in Fig. 3 nearest to view. To do this, the adjusting-screw 22 is backed out of its seat in the flange 21, thereby permitting the flange to drop while the screw is being rotated, and when the flanged end has been lowered the requisite distance the adjusting-screws 23 will be run into their seats until their heads abut against said flange, at which point the block 20 will be firmly locked. To reverse this operation, the adjusting-screws 23 are backed out of their seats the desired distance, after which the screw 22 is rotated to the right, it being assumed, of course, that it has a right-hand thread, until the upper face of the flange abuts against the heads of said screws 23, at which time the block is locked in its elevated position. During the raising or lowering of the block the adjacent end of the roll 5 is of course being carried therewith. In trammimg it may be necessary to adjust both blocks 20 either by raising or lowering the same in order to bring the surfaces of two rolls into proper relation, or it may be necessary to manipulate only one of the blocks to accomplish the desired end. Trammimg of the rolls, however, can be quickly secured by

the means just set forth. Such trammimg means when adjusted serve to maintain the rolls in the correct relation and being, as will hereinafter appear, independent of the mechanism for shifting the bearings 7 cannot be affected when such bearings are moved back and forth to vary the distance between the rolls or to throw them well out of contact. The movable bearings or slides 7 have upon their under sides the depending lugs 25, which are adapted upon the back and forth motion of the slides to traverse channels 26 in the framework 2. The threaded ends of rods 27 extend through such depending lugs 25 and are embraced at opposite sides of the latter by check and holding nuts, each denoted by 28. The rods 27 extend through the upper ends of the rock-arms 29, fulcrumed between their ends to the framework 2 and the lower arms of which project through slots in said framework, and they are connected to actuating devices, hereinafter more particularly described, for effecting the shifting bodily of the slides of the respective low-speed rolls individually or simultaneously. The outer end of the rod 27 at the left is provided with a hand-wheel 30 in the form of a nut threaded thereto and which abuts against the upper outer side of the adjacent rock-arm 29, a like hand-wheel or nut 30 being threaded onto the rod 27 at the right and abutting against the inner upper side of the adjacent rock-arm 29. On the upper inner side of the rock-arm at the left is a socket to receive the coiled push-spring 31, bearing against the adjustable collar 32 on the coöperating rod, said collar 32 being situated upon the inner side of the coöperating rock-arm 29. A like collar 32 is fastened to the rod 27 on the right upon the outer side of the adjacent rock-arm and receives the thrust of a coiled push-spring 31 exactly like the one just mentioned, the inner end of which fits in a socket upon the outer upper side of the coöperating rock-arm 29. By turning either of the adjusting hand-wheels to the right the coacting slides 7, through the intermediate mechanism, will be moved toward the companion fixed bearings 6, the spring 31 adjacent thereto being put under tension by the movement of the rod 27. Upon the reverse movement of the hand-wheel the rod 27 will be moved in a direction to carry the appropriate slides away from the fixed bearings by means of the appropriate coiled spring 31. The hand-wheels or nuts 30 in connection with the springs 31 and allied parts constitute means for adjusting the movably-mounted or low-speed rolls toward or from the complemental rolls in order to regulate the grade of the product.

To the lower ends of the rock-arms 29 are pivoted the rods 35, each extending inward from its coacting rock-arms and through projections or ears 36 upon the framework and terminating at its inner end in a head 37.

Coiled push-springs 38 surround the rods, the terminal coils of the springs bearing against the projection or ears 36 and also against the stops 39 on the respective rods 35, which stops are shown as consisting of nuts, by means of which the tension of the springs can be readily changed. The presence of the spring 38 provides a yielding mounting for the two rolls 5, so that in case any obstruction passes between the same and the complemental rolls 4 they will recede or give, the shock being taken up by the springs, and when such obstruction has passed by the rolls they will be returned to their initial positions by the springs 38.

Means are provided in connection with the rods 35 for moving the same longitudinally, whereby the bearings 7, connected therewith in the manner hereinbefore described, may be shifted. I will now describe a simple means for securing such longitudinal movement of the rods either simultaneously or one pair independently of the other, it being understood that two rods are connected with the movable bearings for each low-speed or shiftable roll 5.

The rock-shafts 40 are supported in horizontal alinement with each other by the framework 2, the opposite ends of the rock-shafts extending beyond the side faces of such framework and having wrist or crank pins 41 (see Fig. 4) extending through perforations in the heads 37 of the rods 35. One rock-shaft 40 carries at one end a hand-lever 42, the other rock-shaft having at the other end a similar lever, also designated by 42. These rock-arms are so connected with the shaft that when a miller faces either what is shown as the left or right in Figs. 1 and 2, respectively, the hand-lever 42 will be within reach of his right hand in order that the same may be manipulated to simultaneously operate two rods or all four rods 35.

Referring to Fig. 1, the wrist-pins 41 are shown as provided with depending arms 43, having pins 44 at their lower or free ends to fit notches in the under side of the bar 45, terminating at its outer ends in handles 46. This bar constitutes a coupler for normally operatively connecting the two rock-shafts 40, and hence the movable bearings or slides 7, whereby the latter may be operated in unison. In Fig. 1 the coupler-bar is shown as connecting the arms 43. Should it be desired to simultaneously move the bearings of the two rolls 5, either hand-lever 42 may be grasped, and by swinging the one downward or the other upward the two shafts 40 will, by means of the coupler-bar 45, be simultaneously rocked. When this is done, the upper end of the rock-arms 29 at the left in Fig. 1 will be swung inward, the upper end of the rock-arm 29 on the right-hand side of the figure being swung outward to thereby move all the bearings 7 away from the coöperating and

stationary bearings 6. This procedure is followed when it is desired to throw the mill out of action for any reason. By grasping either lever 42 and lifting the adjacent end of the 5 coupler-bar 45 by means of the handle 46 to disengage the same from the appropriate pin 44 the bearings for the coacting movable roll can be moved away from the fixed bearings of the complementary roll. This operation 10 takes place in case the feed of the material to the rolls be stopped, which in some cases occurs through a clogging of the supply-spouts and is a common occurrence in mills. The rolls when the material is not passing through 15 the same during their rotation would naturally interfere with each other, and this is especially the case when they are corrugated or fluted. When they run approximately in contact free of the material, they will be 20 damaged to a more or less extent. In the ordinary type of grinding-mills, where two pairs of rolls are built together, it is necessary for the operator in a case like that just mentioned to spread apart both pairs of rolls, and 25 when he comes to readjust or reset them he has double labor, which is very annoying and expensive. In some makes of rolls each pair of rolls has been built separately and independently of the other. With this arrangement 30 the operator is obliged to work from one side of the machine to the other in order to spread both pairs, which also possesses the same disadvantages as well as consuming considerable time. Rolls are usually placed 35 in a mill on the lower or first floor in a line running in number from two to twenty-five machines. Thus it will be seen that the labor connected with spreading each pair of rolls independently of the other means that 40 the operator must pass down one side of the line and up the other. He must repeat this procedure when the rolls are put into their grinding relation. By virtue of my invention 45 an operator can spread any number of rolls in his line without interfering with any other pair, or he can spread or throw together any two pairs of rolls with a single movement of a lever.

The mechanism described therefore constitutes 50 a simple and efficient one for quickly throwing either or both of the adjustably-mounted rolls 5 away from the relatively stationary rolls 4. The rock-arms 29 are provided with stops 47, adapted to engage 55 the upper side of the framework 2 when said rock-arms are in a vertical position. These stops prevent the movably-mounted rolls 5 from being carried into too close contact with the relatively stationary rolls 4. When 60 either or both of the hand-levers 42 are actuated by the operator, the springs 38 are placed under compression, so that when said hand-levers are released the springs will aid in returning the movable bearings 27, and hence 65 the rolls 5 carried thereby, to their primary

positions. The coupler-bar 45 is free of the arms 43, so that it can be readily raised and dropped into its normal position.

The invention is not limited to the exact construction hereinbefore described, for many 70 variations may be adopted within the scope of my claims.

Having described the invention, what I claim is—

1. A grinding-mill including two pairs of differentially-speeded coöperative rolls and bearings therefor, the bearings for the high-speed rolls being stationary and those for the low-speed rolls being movable toward and from the companion stationary bearings, and 80 the bearings for the low-speed rolls both being on the same side of the bearings for the high-speed rolls.

2. A grinding-mill including a roll, stationary bearings for supporting said roll, a 85 pair of slides mounted for movement toward and from the stationary bearings, a second roll carried by the slides, rods connected with the slides, rock-arms connected at their upper ends to the respective rods, rods connected 90 to the lower ends of the rock-arms, and manually-controlled means for moving the last-mentioned rods longitudinally.

3. A grinding-mill including a roll, stationary bearings for supporting said roll, a 95 pair of slides mounted for movement toward and from the stationary bearings, a second roll carried by the slides, rods connected with the slides, rock-arms connected at their upper ends to the respective rods, rods connected 100 to the lower ends of the rock-arms, a rock-shaft having crank-pins at its opposite ends, the last-mentioned rods being perforated to receive said crank-pins, and an actuating-lever connected with the rock-shaft.

4. A grinding-mill including a roll, stationary bearings for supporting the same, a pair of slides, pivotally-mounted blocks on said slides, a second roll directly supported by said pivotally-mounted blocks, rods connected with the slides, rock-arms yieldingly connected at their upper ends to the said rods and provided with stops adapted normally to engage the framework of the machine, rods connected with the lower ends of the rock-arms, a rock-shaft having crank-pins at its 115 opposite ends, said last-mentioned rods being perforated to receive said crank-pins, and an actuating-lever connected with said rock-shaft.

5. A grinding-mill including a roll, stationary bearings for supporting said roll, a pair of slides, pivotally-mounted blocks on said slides, a second roll supported by the pivotally-mounted blocks, means for adjusting the pivotally-mounted blocks, a pair of rods connected with said slides, rockers provided with stops to normally engage the framework of the machine, the upper ends of the rockers being perforated to receive said 125 130 135 140 145 150

rods, springs surrounding the rods and bearing at one end against the rockers, stops upon the rods for engaging the opposite ends of the springs, a second pair of rods connected with 5 the lower ends of the rockers, springs surrounding the last-mentioned rods, the latter having stops to receive one end of the springs and the other end of the springs bearing against the framework, a rock-shaft having 10 crank-pins at its opposite ends, said last-mentioned rods being perforated to receive the crank-pins, and an actuating-lever for said rock-shaft.

6. A grinding-mill including two pairs of 15 coöperating rolls, one roll in each pair being bodily shiftable relatively to the other roll, a

pair of rock-shafts operatively connected with and adapted, on their motion, to move the respective shiftable rolls, a hand-lever carried by each shaft, said hand-levers being 20 upon opposite sides of the mill, rock-arms connected with the rock-shafts, both on the same side of the mill, having projections, and a notched coupling device, the notches of which are adapted to receive said projections. 25

In testimony whereof I have hereunto set my hand in presence of two subscribing witnesses.

HARRY C. ROBINSON.
